L. FIRMBACH, SR

RADIOCABINET

Filed March 5, 1924

INVENTOR

L. Firmbach, Sr.

BY *L. Ledermann*
ATTORNEY

UNITED STATES PATENT OFFICE.

LOUIS FIRMBACH, SR., OF RIDGEWOOD, NEW YORK.

RADIOCABINET.

Application filed March 5, 1924. Serial No. 696,944.

To all whom it may concern:

Be it known that I, LOUIS FIRMBACH, Sr., a citizen of the United States, residing at Ridgewood, in the county of Queens and State of New York, have invented certain new and useful Improvements in Radiocabinets, of which the following is a specification.

This invention relates to cabinets particularly designed for mounting of a radio receiving set, and the main object is to provide a cabinet both useful and ornamental as an article of furniture. The cabinet is constructed with a plurality of compartments exposed by opening of doors, the latter being positioned so that all compartments may be open at the same time.

Another object is to provide a novel method of locking the radio set compartment. The door is locked intermediate its length in the usual manner, and at its sides the novel locking means are employed.

These and other objects will become apparent in the description below, in which characters of reference refer to like-named parts in the drawing.

Referring briefly to the drawing, Figure 1 is a front elevational view of the radio cabinet.

Figure 2 is a side elevational view of the same, the broken lines indicating the doors when partly opened.

Figure 3 is a perspective view of the cabinet with the doors partly opened to expose the interior.

Figure 4 is a sectional elevational view thru a corner of the cabinet and door, showing the auxiliary locking device.

Figures 5 and 6 are perspective views of the locking elements.

Referring in detail to the drawing, the numeral 10 indicates the front legs of the cabinet. Said legs are joined to the rear legs 11 by side walls 12, a rear wall 13, and braces 14 and 15. The upper edge of the brace 14, and the upper and lower edges of the brace 15 are trimmed with ledges 16 designed to produce an ornamental effect. The lid 17 is hingedly connected to the rear wall 13 of the cabinet and may be swung open to expose the interior of the upper compartment 18. The side of the upper compartment is also provided with a door 19 supported on hinges 20. Said door is provided with a lock 21 whose keeper is mounted on the underside of the lid 17, thus locking the lid

17 and door 19 in closed position simultaneously. The side edges of the swing corners of the door 19 are provided with sleeves 22 which are embedded in the door and have internally flanged ends which lie flush with the side surface of the door. Said sleeves provide housings for the flanges 23 of the plungers. The latter have hollow spherical projections 24 in which horizontal diametral slots 25 are formed. The flanges 23 are urged outwardly by springs 26^a anchored in the housings, thus urging the heads 24 into recesses 26, the latter being formed in the upper ends of the legs 10. Openings 70 pass thru the legs and communicate with the recesses 26. In said recesses, studs 27 are rotatably mounted, these studs being retained in the openings by a flanged portion thereon. The outer ends of the studs are provided with wing nuts 28 which are used when rotating said studs and a flat blade 29 extends from the flanged ends of the studs and has an enlarged flattened end 30, this blade being adapted to pass thru the slot 25 of elements 24. The cabinet is divided into two compartments of which 18 is the upper, and 31 the lower, the upper compartment having a floor 32, and the lower compartment a similar floor 33. The lower compartment is provided with a pair of doors 34 and 35, the latter having a knob 36 thereon and a lock which retains the doors in closed position. Said doors open in a vertical plane and are supported on hinges 37. 90

The radio cabinet, as previously stated, is used in combination with radio sets, which is mounted in the upper compartment 18, the panel board 38 of the radio set being shown partly in Figure 3. The accessories to a radio unit such as head sets and the like, may be stored in the compartment 31. When repair is necessary to the radio set, the lid 17 may be rotated and lifted about its hinges. The lid 17 and door 19 are normally locked by member 21, as the bolt of the lock 21 engages the keeper mounted in the lid 17. In order to prevent tampering with this latch, the novel type of side lock, illustrated in Figure 4, is mounted on the corners of the door 19. As the door 19 is rotated to the closed position, the spherical heads 24 will be depressed against the tension of the spring 26^a. This loosens the element 24 into the sleeve 22 and permits passage of the door to the closed position after which member 24 will again be urged out.

wardly by the spring 26^a and is received in the recess 26. As this occurs, the blade 29, projecting from the stud 27 in a normally horizontal position must be in vertical position, that is, aligned with the slot 25 of member 24. This permits the blade to slide thru the slot the latter also extending in a horizontal plane into the hollow portion of member 24, and when said blade is rotated, 10 the enlarged end 30 will engage the interior of member 24 and prevent the same from being moved or depressed. In this manner, the door 19 still remains in locked position when the lock 21 is opened to permit the lid 17 to 15 be lifted.

I claim:

1. In combination with a horizontally hinged door means for latching the corners of said door in closed position either releasably or positively, comprising sleeves embedded in the corners of the door, said sleeves having an internal shoulder, a hemispherical member slidable and adapted to partly project from said sleeve, a flange on 25 said hemispherical member movable within the sleeve, a spring engaging the flange of the hemispherical member and adapted to urge the latter to project, said door being adapted to be rotatable in a frame, the 30 frame having recesses therein adapted to receive the projecting end of the hemispherical

member, and means in said frame cooperating with the door for engaging the hemispherical member to lock the latter in extended position.

2. In combination with a horizontally hinged door means for latching the corners of said door in closed position either releasably or positively comprising sleeves embedded in the corners of the door, said sleeves having an internal shoulder, a hemispherical member slidable and adapted to partly project from each of said sleeves, a flange on said hemispherical member movable within the sleeve, springs engaging the 45 flanges of the hemispherical members and adapted to urge the latter to project, said door being adapted to receive the projecting end of the hemispherical members, said hemispherical members each having a diametral slot therein, studs rotatable in the frame, said studs each having a flat end adapted to pass thru the slot of the corresponding hemispherical member to lock the latter in projected or extended position positively when said stud is rotated to a position where the enlarged end is not aligned with the slot, and wings on said studs for rotating the latter.

In testimony whereof I affix my signature.

LOUIS FIRMBACH, Sr.
